LADDER CONSTRUCTION

James Kydd, Ozone Park, N. Y., assignor to
 Metropolitan Device Corporation, Brooklyn,
 N. Y., a corporation of New York

Application February 16, 1944, Serial No. 522,541

2 Claims. (Cl. 228—48)

1

The invention herein disclosed relates to a portable ladder construction of a kind that is especially suitable for servicing overhead equipment in factories.

In servicing overhead equipment in factories, it is difficult and in some cases impossible to use an ordinary ladder. Many factories are constructed with unusually high ceilings and often without any protuberances against which the upper edge of a ladder may be steadied. In addition machines and other equipment are often arranged in rows forming narrow aisles while much of the overhead equipment, such as electric lights, for example, are directly over the machines.

An object of this invention is to provide a portable ladder construction which is entirely supported at the base and which is serviceable when extended at an angle to the vertical. Another object of the invention is to provide a ladder of this kind that is readily and easily moved from place to place and then manipulated by a single person. Another object of the invention is to provide a ladder of this kind which may be readily and easily secured in any location or position.

The foregoing objects and certain advantages that will hereinafter appear are realized in the embodiment of the invention illustrated in the accompanying drawings and described in detail below.

The drawings include:

Fig. 1 which is a side elevation of a portable ladder embodying the invention;

Fig. 2 which is an end elevation of the ladder support with the ladder in elevation;

Fig. 3 which is a fragmentary end elevation of the lower end of the ladder;

Fig. 4 which is a sectional side elevation of the same;

Fig. 5 which is an enlarged, fragmentary elevation of a hand truck and illustrates the floor lock for the ladder;

Fig. 6 which is an isometric view of the end of the extension section of the ladder and one form of tool box thereon; and

Fig. 7 is a similar view with a modified form of tool box.

The particular ladder illustrated in the drawings is mounted upon an industrial truck, preferably a hand truck 1. This hand truck is of a kind well known and in common use. It includes a platform 2 supported on two sets of wheels 3 and 4. Each of the wheels 4 is journaled on a shaft 5 secured in a fixed bracket 6 secured

2

to the platform. The wheels 3 are mounted in caster brackets 8 which are rotatable about vertical axes. At one end of the truck there are spaced corner posts 9 between which a rail 10 extends. While a hand truck is shown, like portable platforms may be used such as are now used in industries.

The truck is provided with a pair of floor locks which serve, when the ladder is in use, to steady the truck and prevent accidental movement thereof. There is one of these floor locks mounted at each of the posts 9, one of which is shown in detail in Fig. 5. The particular floor lock illustrated includes a tubular metal member

11 which is secured to the post 9. At one end of the tubular member, there is an outwardly extending flange 12 that engages the under side of the platform 2. A rod 13 is slidably in and extends through the member 11. At its upper end, the rod is bent to form a handle 14, and to the lower end of the rod, there is secured a floor-engaging shoe 15. Between flange 12 and a collar 16, secured on the rod 13 just above the shoe 15, there is a spring 17 which acts to press the shoe 15 against the floor. When it is desired to move the truck, the rod 13 is lifted manually against the action of the spring 17. A catch bracket 18 is provided on the post 9 for engaging the handle 14 and holding the shoe 15 out of contact with the floor. The handle is first elevated and then rotated to engage the catch bracket. Screw operated floor locks may, of course, be used.

On the platform 2, there is a ladder base 19. This is a very heavy base preferably made up of scrap steel embedded in cement to give the base great weight. A pivot rod 20 extends from the platform 2, to which it is secured, through the base 19 and a rotatable spider 21, rotatable about the rod 20 and on a plate 22 secured on the base. On this rotatable spider, which may desirably consist of a single casting having four radial arms, the frame for supporting the ladder is mounted. This frame consists of two spaced, vertical, parallel channel irons 23 and two channel irons 24 inclined to the horizontal. Each of the vertical channel irons is secured at one end to the rotatable spider and extends substantially perpendicularly from the plane thereof. Each inclined channel iron 24 is secured at one end to the horizontal spider and at the other end to the upper end of the vertical channel iron 23. These channel irons form a pair of spaced, rigid, triangular uprights between which the ladder is pivotally mounted.

The ladder illustrated is of the adjustable, extension type having two sections 25 and 26, the section 26 being slideable on the section 25 in the usual manner. The lower section 25 of the ladder is mounted on a pivot 27 extending through the side rails 28 and 29 of the section 25 and through the frame uprights at the point where the elements 23 and 24 are joined together.

At the lower end of the section 25 of the ladder, there are mounted counterweights 30 and 31, one secured to the lower end of each of the side rails 28 and 29. In the counterweight 30, there is slidably mounted a pin 32 that extends perpendicularly to the plane of the side rail 28. A similar pin 33 is slidably mounted in the counterweight 31. These pins cooperate with angularly disposed, spaced frame members 34 and 35 that are secured to the rotatable spider. The lower end of the ladder swings between these two frame elements. Each of the frame elements 34 and 35 has a series of openings 34a, 35a therethrough disposed in an arc concentric with the axis about which the ladder pivots. The holes 34a, 35a through the frame elements are of a diameter to receive the pins 32 and 33 respectively. When the pins extend into aligned openings in the frame elements 34 and 35, the ladder is positioned in one of several angular positions and is secured in that position by the interengagement of the pins and the frame elements.

The pins 32 and 33 are spring-pressed in opposite directions so that each pin is urged in a direction to enter the openings in the frame elements 34 and 35. For this purpose, there is provided a cylindrical element or sleeve 36 that extends between and that is rigidly fastened to the counterweights. The pins 32 and 33 extend into the cylindrical element 36. A spring 37 within the element 36 presses on the ends of the pins within the sleeve 36. Tubular sleeves 37' and 38 are slidably mounted on the element 36. A pin 39 extends from the pin 32 and through a diametrical, longitudinal slot in the element 36 and through the sleeve 37', and a pin 40 extends from the pin 33, a slot provided therefor in the element 36 and into the sleeve 38. The slots in the element 36 through which the pins 39 and 40 extend are of sufficient length to permit the pins 32 and 33 to be moved toward each other a distance to disengage them from the openings in the frame elements 34 and 35, the sleeves 37' and 38 forming hand-grips for this purpose. The pins 39 and 40 also limit, by abutment with the ends of the slots, the outward movement of the pins 32 and 33.

From the description of this construction, it will be seen that when it is desired to position the ladder the operator grasps the sleeves 37' and 38 and draws them inwardly until the pins 32 and 33 are free of any openings in the frame elements 34 and 35. With these pins thus retracted, the ladder is moved about its pivotal connection to the desired position when the pins are released and the ladder moved slightly until the bolts, by virtue of the action of the spring, move into the desired pair of openings through the frame elements 34 and 35. The ladder is thus positioned and secured in position.

When the ladder is raised and the extension section 26 is extended, there is a considerable force exerted at the counterweights, a force that is somewhat greater than that which can be resisted by one individual. Thus, if the pins 32 and 33 are withdrawn in an attempt to lower the ladder to the position shown in Fig. 1, while the

extension section is extended, the ladder will drop. This may result in injury to the operator, the ladder or both. To prevent this a safety lock is provided such that it is impossible to withdraw both pins 32 and 33 while the extension section is raised or extended.

The safety lock is arranged to engage the pin 39 when the extension section 26 is raised. For this purpose, the pin 39 extends beyond the sleeve 37'. The safety lock is mounted in a stationary bracket 41 mounted on the counterweight 30. A pair of rods 42 and 43 are slidably mounted in the bracket 41. At one end, the rods 42 and 43 are secured to a plate 44 which extends into the path of an angle iron 45 on the extension section 26. The other end of the rods are secured to a catch 46 which consists of an angle iron having a flange 47 with a notch 48 therein. Springs 49, acting between the plate 44 and the bracket 41 resiliently urge the rods 42 and 43 upwardly in which position the pin 39 is received in the notch 48 of the catch 46. In this position, the pin 32 cannot be withdrawn.

When the extension section 26 is raised, the catch 46 automatically moves into position to engage the pin 39. When the extension section is lowered, the angle iron 45 engages the plate 44 and moves the catch 46 to the position illustrated in which position the pin 39 is released. Thus, as the operator requires both hands to release both pins 32 and 33, the ladder cannot be released unless the extension section is lowered. A chain 50 serves to hold the ladder in a horizontal position when it is not in use.

In Fig. 6 there is illustrated a tool box 51 mounted upon the end of the extension section 26, spaced therefrom and arranged to remain horizontal irrespective of the position of the ladder. For the purpose of mounting the tool box 51, brackets 52 and 53 are carried by the rails of the section 26. A pair of converging links 54 and 55 extend from and are secured to the bracket 52. A like pair of converging links 56 and 57 extend from the bracket 53. The box 51 is pivotally secured to these converging links at their apex. A stiffening rod 58 extends between the brackets 52 and 53.

With some ladders of the type described, it is desirable to have provision at the top of the extension section for raising loads greater than a man can carry up the ladder. For this purpose, a special tool box is provided at the top so constructed that loads of approximately five hundred pounds may be elevated by means of a chain block supported by the tool box. This tool box performs two functions. It not only provides the support for the chain block but also acts as a box girder to resist the collapsing force at the end of the ladder due to the weight suspended from the chain block.

Such a tool box construction is illustrated in Fig. 7. Here a tool box 59 is pivotally supported between, and at the ends of, brackets 60 and 61 extending from the side rails substantially perpendicularly to the plane of the section 26. A rod 62 extends between the brackets inwardly of the tool box. On the bottom of the tool box there is an eye 63 for a chain block.

It will be obvious that various changes may be made by those skilled in the art in the details of the embodiment of the ladder construction illustrated in the drawings and described in detail above within the principle and scope of the invention as expressed in the appended claims.

I claim:

1. In a portable ladder construction of the kind described, the combination comprising a frame, a ladder having side rails and rungs pivotally mounted in the frame, the ladder including an extension section, means carried by the frame and the ladder for securing the ladder in various angular positions, and means actuated upon movement of the extension section to extended position for locking said securing means.

2. In a portable ladder construction of the kind described, the combination comprising a frame, a ladder having side rails and rungs pivotally mounted in the frame, the ladder including an extension section, means carried by the frame and ladder for securing the ladder in various angular positions, interengaging means for locking said securing means when the extension section is in extended position, and means engageable by said extension section in its lower position for releasing said interengaging means.
